UNITED STATES PATENT OFFICE.

HARMAN P. ROGERS, OF ALBION, INDIANA.

DESIGN FOR A SPOON, FORK, OR SIMILAR ARTICLE.

No. 40,122.

Specification for Design.

Patented July 6, 1909.

Application filed March 31, 1909. Serial No. 487,095. Term of patent 7 years.

To all whom it may concern:

Be it known that I, HARMAN P. ROGERS, a citizen of the United States, residing at Albion, in the county of Noble and State of Indiana, have invented a new, original, and ornamental Design for a Spoon, Fork, or Similar Article, of which the following is a specification, reference being had to the accompanying drawings, forming a part thereof, and in which—

Figure 1 is an elevation of the obverse side

of an article embodying my invention, and Fig. 2 is a view of the reverse side of an article showing my new design.

I claim—

The ornamental design for a spoon, fork or similar article, as shown.

HARMAN P. ROGERS.
